UNITED STATES PATENT OFFICE.

ARTHUR R. BAKER, OF INDIANAPOLIS, INDIANA, ASSIGNOR, BY MESNE ASSIGNMENTS, TO CHARLES G. McCUTCHEON, OF INDIANAPOLIS, INDIANA.

IGNITER TRIP MECHANISM.

1,419,711.

Specification of Letters Patent. Patented June 13, 1922.

Application filed July 20, 1918. Serial No. 245,849.

To all whom it may concern:

Be it known that I, ARTHUR R. BAKER, a citizen of the United States, residing at Indianapolis, in the county of Marion and 5 State of Indiana, have invented new and useful Igniter Trip Mechanisms, of which the following is a specification.

It is the object of my invention to improve and simplify the operating mechanism for oscillating ignition magnetos for internal combustion engines; to make such operating mechanism accurate in its action, so that it trips at a predetermined point with substantially no variation; to eliminate 10 all extraneous tripping devices for producing the tripping action; to minimize the tendency to flex the operating rod, and in consequence the vibrations which destroy accuracy; to produce an accurate change in 15 this predetermined point for running and starting conditions; to produce a tripping action which does not interfere with the quick snapping of the oscillating member of the magneto, and which in consequence does 20 not lessen the ignition spark; to minimize 25 wear; and to provide a device which may be used interchangeably with either side uppermost without any change, and may be used for either right or left hand mounting 30 by the mere selection between right and left hand carrying eccentrics, as conditions require.

The accompanying drawings illustrate my invention. Fig. 1 is an elevation of an oscillating magneto and part of the associated engine, with my improved operating mechanism, showing the eccentric in starting position; Fig. 2 is a plan of the trip lever and eccentric, with some parts broken away, 40 as arranged for left hand mounting, with the eccentric in running position; Fig. 3 is a view similar to Fig. 2, as arranged for right hand mounting, which right hand mounting is also shown in all the other figures of the 45 drawing except Fig. 2; Fig. 4 is an elevation, in partial section, of the trip lever and its mounting, showing its relation to the trip finger of the oscillating member of the associated magneto and to the electrodes 50 when the parts are at rest, and showing the eccentric in running position; and Fig. 5 is a view similar to Fig. 4, though wholly in elevation, showing in full lines the relation of the parts just at the moment of tripping 55 and in dotted lines the parts after tripping.

The internal combustion engine 10, of which only a fragment is shown, has its ignition spark supplied by a magneto 11, which is of the oscillating type having a movable member mounted on a shaft 12 and 60 biased to a normal position by a pair of returning springs 13 acting between two fixed posts 14 and two pins 15 on a cross head 16 fixed on said shaft 12. The cross head 16 has a finger 17 which engages a finger 18 65 connected with the movable electrode 19 (Fig. 4) and moves such movable electrode away from the fixed electrode 20 when the cross head 16 and the movable member of the magneto are moved in a counterclockwise direction (Figs. 1 and 4) from their 70 normal position, or to the dotted line position shown in Fig. 5. The finger 18 is biased toward the finger 17, and the movable electrode 19 toward the fixed electrode 20, by a 75 suitable spring 21. The magneto and the electrodes are both conveniently mounted on a bracket 22, which is suitably fastened to the engine 10. So far this is a standard construction.

The engine 10 has the usual rotating cam 25, which co-operates with a roller 26 on the end of a reciprocable rod 27 to produce the desired movement of such rod. The rod 27 operates the magneto; and may also operate 85 the exhaust valve mechanism, if desired, as indicated by the extension of said rod to the left in Fig. 1 past the magneto, though this forms no part of the present invention. A clamp 28 is mounted on the rod 27 in any 90 desired position therealong, and is held in such desired position by clamping screws 29. The clamp 28 is provided with a laterally projecting pin 30; on which is an eccentric bushing 31 provided at the outer end of the 95 pin 30 with a flange 32, a pair of operating wings 33, and two movement-limiting fingers 34 projecting from the flange 32 in the plane thereof. The bushing 31 is held on the pin 30 in any suitable manner, as by a spring 100 ring 35. A trip lever or pusher is pivoted at one end on the eccentric bushing 31, between the body of the clamp 28 and the flange 32. This trip lever comprises a sleeve 36 and a bolt 37, the latter being screwed 105 into the open end of such sleeve 36 and held in proper position therein by a lock nut 38. A finger 39 projects from the pivot hub of the sleeve 36 either downward (Figs. 1 and 4) or upward (Fig. 5), and a tension spring 110

40 connects this finger 39 to a lug 41 on the clamp 28. The trip lever is placed on the bushing 31 with the finger 39 upward or downward, according as the lug 41 and 5 spring 40 are above or below the trip lever; for this will vary with different engines. The trip lever may thus be reversed in position, as required by the character of the bracket 28 and the engine conditions, without necessitating any change in the trip lever itself. In either case the spring 40 tends to move the trip lever in a clockwise direction (Figs. 1, 4, and 5) to produce engagement of the sleeve 36 with an adjustable stop screw 10 42 mounted in a lug 43 on the clamp 28. The free end of the bolt 37 of the trip lever has an operating head 44, which co-operates with a trip finger 45 on the cross head 16. That edge of the trip finger 45 which engages the head 44 is rounded; and the edges of the bolt head 44 are correspondingly rounded, for though only the upper edge of the bolt head operates for a given position the rounding of all four edges is provided 15 to allow for wear and to permit the aforesaid reversal of the trip lever to bring the finger 39 either upward or downward. The adjustment of the screw 42 controls the height of the upper rounded edge of the bolt 20 head 44 with relation to the rounded edge of the trip finger 45, and in conjunction with the adjustment of the clamp 28 on the rod 27 determines the tripping point. By turning the eccentric 31 through half a revolution, the trip lever is shifted as a whole to the left (for running) and to the right (for starting), without varying the vertical position of the head 44. In order to ensure this, the surface of the eccentric 31 is provided 25 with two retaining notches at its thickest and thinnest points respectively, and a spring-pressed stop button 47 is mounted within the sleeve 36 in position to engage one or the other of these notches 46 according as the eccentric is in running or starting 30 position; the stop button 47 is fastened to one end of a compression spring 48, the other end of which is fastened to the inner end of the bolt 37, for the threads of the bolt 37 35 are not for adjustment purposes. In addition to the positioning stop button 47, the movement of the eccentric 31 past the starting or the running position is prevented by the engagement of the movement-limiting 40 fingers 34 with one or the other of two lateral bosses 49 projecting from the two side faces of the sleeve 36. The fingers 34 are arranged so as to require the movement of the thickest part of the eccentric over the 45 pivot pin 30 and to prevent such thickest part from moving under the pin 30 when the eccentric is turned from starting to running position; so that during the intermediate 50 parts of such movement the pivotal end of 55 the trip lever is raised and the operating 60

head 34 is lowered with relation to the positions they occupy when the eccentric is in either starting or running positions. This prevents delay of the tripping beyond the proper point, and avoids any possible break- 70 age of the machine by jamming, in case a tripping action occurs as the eccentric is being moved from starting to running position. This protective action is augmented by reason of the fact that the turning of the 75 eccentric bushing from starting to running position, which turning occurs while the engine is in operation, is in a counterclockwise direction from the position shown in Fig. 1 to the position shown in Figs. 4 and 5, so 80 that the drag of the stop button 47 in the starting notch 46 of the eccentric 31 may carry the trip lever in a counterclockwise direction around its pivotal axis if it produces any movement at all of such trip lever, 85 thus lowering the operating head 44 so that though a complete missing of a firing operation may occur jamming of the parts is effectually prevented.

In different engines, the operating rod 27 90 and the magneto and its associated parts may be located on different sides of the engine. With the right hand mounting, shown in Figs. 1, 4, and 5, with the rod 27 and the magneto on the right hand side of 95 the engine as viewed from the cylinder head end, the pin 30 projects through the pivot hole in the trip lever in the opposite direction from what it does with the left hand mounting, which is indicated in Fig. 2 and 100 in which the rod 27 and the magneto are on the left hand side of the engine as viewed from the same end. In both cases the eccentric bushing projects through the pivot hole in the opposite direction from the pivot pin 105 30, so that the flange 32 will be at the outer end of said pin. The trip lever may have either the right or the left hand mounting without any change; but in order to provide for the desired movement of the eccentric 110 bushing so that its thickest portion will always pass over and not under the pivot pin 30 it is necessary to provide such bushings in rights and lefts, shown in Figs. 3 and 2 respectively. The only difference between the right and left hand bushings is that the flange 32 with the wings 33 and motion-limiting fingers 34 are shifted 180° 115 axially, with respect to the body of the eccentric bushings. Thus, as is clear from 120 Figs. 2, 3, 4, and 5, the same trip lever may be used for both right and left hand mountings and in either mounting with the finger 39 either upward or downward; and either eccentric bushing may be used with the 125 finger 39 either upward or downward for the right hand or the left hand mounting respectively.

In operation, the reciprocable rod 27 is reciprocated by the cam 25 in the usual 130

manner, and carries the clamp 28 and trip lever 36-37 with it. As these move to the left, the operating head 44 engages the rounded edge of the trip finger 45, and produces a clockwise movement of the movable member of the magneto and the cross head 16 against the action of the springs 13 from the position shown in Fig. 4 to the position shown in full lines in Fig. 5. During this movement, the rounded edge of the trip finger 45 has a combined sliding and rolling movement on the face and upper rounded edge of the operating head 44, until substantially the position shown in full lines in Fig. 5 is reached. At this point the returning pull of the springs 13, acting through said rounded edges of the operating head 44 and trip lever 45, which serve as cams of gradually increasing effect and produce a gradually increasing downward component of pressure on the operating head 44, causes such cam action to throw the trip lever downward from the full line position to the dotted line position in Fig. 5, and as the trip lever thus swings downward the cross head 16 with its associated parts swings in a counterclockwise direction from the full line position to the dotted line position shown in Fig. 5. This movement of the cross head 16 and of the movable member of the magneto with it is produced by the action of the springs 13; but the momentum of the moving parts carries them past their normal or central positions, at which point the speed is the highest, so that the finger 17 strikes the finger 18 and snaps the movable electrode 19 away from the fixed electrode 20, as indicated in dotted lines in Fig. 5. This produces the desired ignition spark between the electrodes 19 and 20. The returning springs 13 return the cross head 16 and the movable electrode to normal position after one or two oscillations, leaving the parts as shown in Fig. 4. As the trip lever 36 is snapped down out of the way of the trip finger 45 at the beginning of the counterclockwise movement, no drag on such movement occurs, and an unretarded snap producing a high voltage and an effective spark is obtained. The point at which the tripping occurs may be varied by adjusting the screw 42; and though this point is at a slightly different time in the cycle under starting and running conditions, with the eccentric bushing 31 in its two positions, by reason of the arrangement of parts the height of the operating head 44 is the same under both conditions, and therefore the amount by which the movable parts of the magneto are turned from normal is likewise the same under both conditions. The change of the position of the eccentric bushing from starting to running merely moves the trip lever bodily to the left relatively to the reciprocating member 27, so as to cause the

tripping to occur at a slightly earlier point in the cycle—that is, so that the spark is advanced. Because the movement of the rounded edge of the trip finger 45 on the operating head 46 is in the main a rolling movement, with very little sliding, and because these parts do not engage with a hammer blow, very little wear occurs, and one adjustment of the screw 42 lasts for a great while, even though the engine is kept in continuous operation.

I claim as my invention:

1. A magneto having an oscillating movable member which is biased to one position, said movable member being provided with a trip finger; in combination with a reciprocable member, and a pusher movably mounted on said reciprocable member and co-operating with said trip finger, said pusher having a rounded operating side through which it engages said trip finger at a varying angle as it moves it, whereby the reaction of the bias of the magneto produces between the trip finger and the pusher an increasing cam action which at a predetermined point pushes the pusher out of the path of the trip finger and permits said bias to move the movable member of the magneto to normal position.

2. A magneto having an oscillating movable member which is biased to one position, said movable member being provided with a trip finger; in combination with a reciprocable member, and a pusher movably mounted on said reciprocable member and co-operating with said trip finger, said trip finger having a rounded operating edge through which it is engaged by an edge of said pusher at a varying angle as it is moved thereby, whereby the reaction of the bias of the magneto produces between the trip finger and the pusher an increasing cam action which at a predetermined point pushes the pusher out of the path of the trip finger and permits said bias to move the movable member of the magneto to normal position.

3. A magneto having an oscillating movable member which is biased to one position, said movable member being provided with a trip finger; in combination with a reciprocable member, and a pusher movably mounted on said reciprocable member and co-operating with said trip finger, said trip finger and said pusher having an inter-engagement the line of pressure transmission through which makes to the line of movement of the pusher relative to the reciprocable member an angle which decreases in the movement of the movable member of the magneto from its normal position by said pusher, whereby the reaction of the bias of the magneto produces between the trip finger and the pusher an increasing cam action which at a predetermined point pushes the pusher out of the path of the trip

finger and permits said bias to move the movable member of the magneto to normal position.

4. A magneto having an oscillating member biased to one position, a trip finger on said oscillating member, a reciprocable operating member, a trip lever pivoted on said reciprocable member and acting longitudinally of itself on said trip finger to move 10 said oscillating member from normal position, said trip finger and trip lever being arranged so that as the trip lever pushes the trip finger the point of engagement travels to produce an increasing component 15 of pressure on the trip lever at right angles to its length, whereby when a predetermined position is reached the trip lever is snapped out of the way by the bias of said oscillating member to permit the trip finger and oscillating member to snap back.

5. A magneto having an oscillating member biased to one position, a trip finger on said oscillating member, a reciprocable operating member, a trip lever pivoted on said reciprocable member and acting longitudinally of itself on said trip finger to move 25 said oscillating member from normal position, said trip finger and trip lever being arranged so that as the trip lever pushes 30 the trip finger the point of engagement passes over an edge to produce a component of pressure perpendicular to the length of the trip lever, whereby at a predetermined point the trip lever is snapped out of the 35 way by the bias of said oscillating member to permit the trip-finger and oscillating member to snap back.

6. A magneto having an oscillating member biased to one position, a trip finger on 40 said oscillating member, a reciprocable operating member, a trip lever pivoted on said reciprocable member and acting longitudinally of itself on said trip finger to move said oscillating member from normal position, said trip finger and trip lever being arranged so that as the trip lever pushes the trip 45 finger the point of engagement passes over an edge to produce a component of pressure perpendicular to the length of the trip lever, whereby at a predetermined point the trip lever is snapped out of the way by the bias 50 of said oscillating member to permit the trip-finger and oscillating member to snap back, and a spring acting on said trip lever 55 in opposition to such perpendicular component of pressure.

7. A magneto having an oscillating member biased to one position, a trip finger on 60 said oscillating member, a reciprocable operating member, a trip lever pivoted on said reciprocable member and acting longitudinally of itself on said trip finger to move said oscillating member from normal position, said trip finger and trip lever being 65 arranged so that as the trip lever pushes

the trip finger the point of engagement passes over an edge to produce a component of pressure perpendicular to the length of the trip lever, whereby at a predetermined point the trip lever is snapped 70 out of the way to permit the trip-finger and oscillating member to snap back, and means for adjusting normal position of said trip lever about its pivot to adjust the point at which such perpendicular component of 75 pressure effects such snapping.

8. A magneto having an oscillating member biased to one position, a trip finger on said oscillating member, a reciprocable operating member, a trip lever pivoted on said reciprocable member and acting longitudinally of itself on said trip finger to move 80 said oscillating member from normal position, said trip finger and trip lever being arranged so that as the trip lever pushes the 85 trip finger the point of engagement passes over an edge to produce a component of pressure perpendicular to the length of the trip lever, whereby at a predetermined point the trip lever is snapped out of the way 90 to permit the trip-finger and oscillating member to snap back, and means for adjusting said trip lever longitudinally with respect to said reciprocable member to vary 95 the point in the movement of the reciprocable member at which such snapping of the trip lever occurs.

9. A magneto having an oscillating member biased to one position, a trip finger on said oscillating member, a reciprocable operating member, a trip lever pivoted on said reciprocable member and acting longitudinally of itself on said trip finger to move 100 said oscillating member from normal position, said trip finger and trip lever being 105 arranged so that as the trip lever pushes the trip finger the point of engagement passes over an edge to produce a component of pressure perpendicular to the 110 length of the trip lever, whereby at a predetermined point the trip lever is snapped out of the way to permit the trip-finger and oscillating member to snap back, the pivotal mounting of said trip lever on said reciprocable member including a pivot pin on one 115 of said parts and an eccentric bushing surrounding said pivot pin and fitting within the other of said parts, and means for positioning said bushing in either of two positions in both of which its thickest and thinnest 120 portions are substantially in the line of the length of said trip lever.

10. A magneto having an oscillating member biased to one position, a trip finger on said oscillating member, a reciprocable 125 operating member, a trip lever pivoted on said reciprocable member and acting longitudinally of itself on said trip finger to move said oscillating member from normal position, said trip finger and trip lever 130

lever being arranged so that as the trip lever pushes the trip finger the point of engagement passes over an edge to produce a component of pressure perpendicular to the length of the trip lever, whereby at a predetermined point the trip lever is snapped out of the way to permit the trip finger and oscillating member to snap back, the pivotal mounting of said trip lever on 10 said reciprocable member including a pivot pin on one of said parts and an eccentric bushing surrounding said pivot pin and fitting within the other of said parts, and means for limiting the movement of said bushing to an angle of which the center produces in the direction of such component of pressure the maximum movement of said trip lever of which said eccentric is capable.

11. A magneto having an oscillating member biased to one position, a trip finger on said oscillating member, a reciprocable operating member, a trip lever pivoted on said reciprocable member and acting longitudinally of itself on said trip finger to move 20 said oscillating member from normal position, said trip finger and trip lever being arranged so that as the trip lever pushes the trip finger the point of engagement passes over an edge to produce a component of pressure perpendicular to the length of the trip lever, whereby at a predetermined point the trip lever is snapped out of the way to permit the trip finger and oscillating member to snap back, the pivotal mounting of 30 said trip lever on said reciprocable member including a pivot pin on one of said parts and an eccentric bushing surrounding said pivot pin and fitting within the other of said parts, and means for positioning said bushing in either of two positions in both of which the position of the free end of said lever in the direction of said component of pressure is substantially the same.

12. A magneto having an oscillating member which is biased to one position, and a trip finger on said oscillating member; in combination with an operating member having a pivot pin, an eccentric bushing mounting on said pivot pin, a trip lever mounted 40 on said eccentric bushing and co-operating with said trip finger, and an abutment carried by said operating member and limiting the movement of said trip lever.

13. A magneto having an oscillating member which is biased to one position, and a trip finger on said oscillating member; in combination with an operating member having a pivot pin, an eccentric bushing mounted on said pivot pin, a trip lever mounted on 50 said eccentric bushing and co-operating with said trip finger, said trip lever being reversible in position on said eccentric bushing.

14. A magneto having an oscillating member which is biased to one position, and

a trip finger on said oscillating member; in combination with an operating member having a pivot pin, an eccentric bushing mounted on said pivot pin, a trip lever mounted on said eccentric bushing and co-operating 70 with said trip finger, said trip lever being substantially symmetrical about its longitudinal axis with respect to its pivotal mounting and also with respect to its operating end so that it may be placed on said 75 bushing in either position without varying the operation.

15. A magneto having an oscillating member which is biased to one position, and a trip finger on said oscillating member; in 80 combination with an operating member having a pivot pin, an eccentric bushing mounted on said pivot pin, a trip lever mounted on said eccentric bushing and co-operating with 85 said trip finger, said trip lever being substantially symmetrical about its longitudinal axis with respect to its pivotal mounting and also with respect to its operating end so that it may be used without change 90 for either right or left hand mountings and may be placed in either position on the eccentric.

16. A magneto having an oscillating member biased to one position, a trip finger on said oscillating member, a reciprocable operating member, a trip lever pivoted on said reciprocable member and acting longitudinally of itself on said trip finger to move 95 said oscillating member from normal position, said trip lever and said trip finger having an interengagement the line of pressure transmission through which varies in direction in the movement of the movable members by said trip lever, and the bias of said oscillating member being sufficiently strong 100 so that it swings the trip lever on its pivot out of engagement with said trip finger when the angle between said line of pressure transmission and the trip lever becomes sufficiently great.

17. A magneto having an oscillating movable member which is biased to one position, said movable member being provided with a trip finger; in combination with a reciprocable member, and a pusher movably mounted 115 on said reciprocable member and co-operating with said trip finger to move said movable member as said reciprocable member moves and by the reaction from the bias of the movable member to push the pusher out of the path of the trip finger to permit said movable member to return when it has reached a predetermined point.

18. A magneto having an oscillating movable member which is biased to one position, said movable member being provided with a trip finger; in combination with a reciprocable member, and a pusher movably mounted on said reciprocable member and co-operating with said trip finger, said trip 125

finger and said pusher having an interengagement the line of pressure transmission through which varies in direction in the movement of the movable member by said pusher, and the bias of said oscillating member being sufficiently strong so that it forces the pusher laterally out of engagement with said trip finger when the angle between said

line of pressure transmission and said pusher becomes sufficiently great.

In witness whereof, I have hereunto set my hand at Indianapolis, Indiana, this 18th day of July, A. D. one thousand nine hundred and eighteen.

ARTHUR R. BAKER.
